ADVERTISING DISPLAY

Otto J. Kralovec, Jr., River Forest, Ill., assignor to General Outdoor Advertising Company, Inc., Chicago, Ill., a corporation of New Jersey

Application January 25, 1955, Serial No. 34,190

Term of patent 14 years

(Cl. D80—1)

To all whom it may concern:

Be it known that I, Otto J. Kralovec, Jr., a citizen of the United States, residing at River Forest, in the county of Cook and State of Illinois, have invented a new, original, and ornamental Design for an Advertising Display, of which the following is a specification, reference being had to the accompanying drawing, forming a part thereof, in which:

Fig. 2 is a top plan view thereof.

I claim:

The ornamental design for an advertising display, as shown.
